UNITED STATES PATENT OFFICE.

BYRON B. HOHSTADT, OF MIAMI, ARIZONA.

MUSIC-LEAF TURNER.

1,183,461.

Specification of Letters Patent. Patented May 16, 1916.

Application filed August 3, 1915. Serial No. 43,438.

To all whom it may concern:

Be it known that I, BYRON B. HOHSTADT, a citizen of the United States, residing at Miami, in the county of Gila, State of Arizona, have invented certain new and useful improvements in Music-Leaf Turners; and I do hereby declare the following to be a full, clear, and exact description of the invention, such as will enable others skilled in the art to which it appertains to make and use the same.

This invention relates to improvements in music leaf turners.

The principal object of the invention is to provide a novel and simple device by means of which the middle loose leaf of a piece of sheet music can be quickly and effectively turned.

Another object is to provide a music leaf turner by means of which the loose leaf of a piece of sheet music can be quickly and easily turned forwardly or backwardly.

Other objects and advantages will be apparent from the following description when taken in connection with the accompanying drawing.

In the drawing: Figure 1 is a front elevation of my improved music leaf turner, Fig. 2 is a side elevation, Fig. 3 is a vertical sectional view on the line 3--3 of Fig. 1, Fig. 4 is a horizontal sectional view on the line 4--4 of Fig. 1.

Referring particularly to the accompanying drawing 10 represents a vertical casing, to the lower end of which is secured a forwardly extending music supporting shelf or ledge 11. In the central portion of the lower end of the front of the casing is formed an opening 12, and secured to the music ledge below this opening, is a bearing bracket 13. A bracket 14 is secured to the top of the casing and extends outwardly over the bracket 13. Journalized in these brackets are the ends of a vertical shaft 15. Carried by the ends of the front of the casing are the clips 16 for holding the ends of the opened back portion of a piece of sheet music. Extending through the center of the casing, from front to rear, is a shaft 17 on the forward portion of which, within the casing, is secured a segmental bevel pinion 18. Mounted within the casing, and in parallel relation with the shaft 15, is a vertical shaft 19, on the upper end of which is secured a segmental bevel pinion 20, said pinion meshing with the before-mentioned

pinion 18. On the lower end of the shaft 19 is a pinion 21 which meshes with a segmental pinion 22 on the lower end of the shaft 15, said pinions engaging through the opening 12 in the front of the casing.

On each end of the casing is pivotally mounted a finger lever 23, the rear end of which is held in normally depressed position by a spring 24. The forward end of the lever is provided with a button 25 for engagement of the finger of the hand. Rigidly secured on the horizontal shaft 17 is a rock arm 26, its opposite ends being provided with weights 26' and extending through openings 27 in the ends of the casing over the inner ends of the finger levers 23. Secured to the vertical shaft 15, and extending radially therefrom, are a pair of transparent sheets of celluloid, or other suitable like material 28. Between these sheets of celluloid is placed the loose leaf of the music, suitable clips, such as shown at 29, being engaged over the upper and lower ends of the celluloid sheets to hold the music leaf therebetween. The weights on the rock arm are adapted to have a limited sliding movement longitudinally of the arms. Then, by depressing the finger lever on which the lowered end of the arm rests, with a quick movement, the arm will be rocked on its pivot, and thus turn the shaft 17. This turning of the shaft 17 causes the turning of the shaft 15, through the intermeshing gears, and the shifting of the celluloid sheets and the music leaf to the opposite side of the casing. This movement causes the other end of the rock arm to be depressed, and by depressing the other finger lever with a quick movement, the arm can be rocked back to its initial position. Thus the music leaf can be readily and quickly turned back and forth, as desired. It will be noted that the weight on the depressed end of the arm will slide to the outermost limit of its movement while the weight on the other end will slide to the innermost limit of its movement. This movement of the weight on the upper end of the arm is such that it destroys a perfect balance, and prevents the rock arm from rebounding after it has been operated.

The device is of simple construction, few parts, and can be readily used on the music shelf of a piano or organ, or on the ledge of a portable music stand or rack.

What is claimed is:

A music leaf turner comprising a casing,

a vertical shaft mounted in the front of the casing and carrying a pinion on its lower end, a vertical shaft mounted within the casing and carrying a pinion on its lower end meshing with the first-named pinion, a forwardly and rearwardly extending rock shaft mounted in the casing, gear connections between the rock shaft and the second-named vertical shaft, radial arms carried by the rock shaft and extending through the ends of the casing, said arms being perfectly balanced, pivoted spring held levers at the

ends of the casing below the ends of the arms and a pair of transparent sheets secured to and extending radially from the first-named vertical shaft for holding the middle loose leaf of a piece of sheet music therebetween.

In testimony whereof, I affix my signature, in the presence of two witnesses,

BYRON B. HOHSTADT.

Witnesses:

W. J. ELLERY,
F. T. VANCE.
